UNITED STATES PATENT OFFICE.

WARREN WAGNER, OF BURKBURNETT, TEXAS.

UNDERREAMER.

1,080,666.

Specification of Letters Patent.

Patented Dec. 9, 1913.

Application filed February 12, 1913. Serial No. 748,033.

To all whom it may concern:

Be it known that I, WARREN WAGNER, a citizen of the United States, residing at Burkburnett, in the county of Wichita and State of Texas, have invented certain new and useful Improvements in Underreamers, of which the following is a specification, reference being had to the accompanying drawings.

10 This invention relates to underreamers such as are employed for reaming wells beneath the lower end of a tube or casing and the invention has for its primary object to generally improve the construction and increase the operating efficiency of a tool of this character, such as is disclosed in my prior Patent Number 1,038,243, issued to me September 10, 1912.

Another object of the invention resides 20 in the provision of improved means for mounting the cutting bits in the mandrel so that they are securely held against lateral spreading movement from their operative positions beneath the lower end of the well casing.

Another and more specific object of the invention is to provide a spring pressed 30 plunger or stem mounted in the mandrel and a key connecting the cutting bits to said mandrel and means carried by the cutting bits to prevent their lateral movement or complete disconnection from the mandrel in the event that said key should be broken, thus obviating the loss of the bits.

35 Another object of the invention is to provide cutting bits of improved form for tools of this character and a separating web therebetween formed upon the lower end of the mandrel, and means for minimizing the 40 wear upon said web induced by the frictional contact of the bits therewith.

A further object is to produce an underreamer which is comparatively simple in its construction, and wherein the bits may be 45 readily removed from the mandrel when it is necessary to sharpen the same.

With the above and other objects in view as will become apparent as the description proceeds, the invention consists in certain

constructions, combinations and arrangements of the parts that I shall hereinafter fully describe and claim.

For a full understanding of the invention, reference is to be had to the following description and accompanying drawings, in which—

Figure 1 is a side elevation of an underreamer embodying the present invention; Fig. 2 is a view looking at right angles to Fig. 1 showing the positions of the cutting bits as the tool is being lowered in the well casing; Fig. 3 is a section taken on the line 3—3 of Fig. 1, showing the device in its operative position; Fig. 4 is a section taken on the line 4—4 of Fig. 3; Fig. 5 is a side elevation of the mandrel, the bits being removed; Fig. 6 is a detail perspective view of one of the cutting bits; and Fig. 7 is a horizontal section of the lower ends of the cutting bits.

Referring in detail to the drawings, 5 indicates the stock or mandrel which is longitudinally bored as indicated at 6, the upper end of said bore being enlarged as at 7 for a purpose which will be later referred to.

The mandrel is provided upon opposite sides with channels 8 and slots 9 connect these channels with the central longitudinal bore 6. The lower ends of the slots 9 are 80 widened or flared as indicated at 10. The opposed walls of the channels 8 are provided with longitudinal guide grooves 11, said grooves gradually widening at their lower open ends as indicated at 12 in Fig. 3. Inclined notches or recesses 13 open into the guide grooves 11 at a point intermediate their ends. The lower end of the stock or mandrel is provided with a central longitudinally extended web 14, the lower end of 90 which is beveled in opposite directions as indicated at 15. The body of the mandrel upon opposite sides of the channels 10 therein is curved upwardly to produce the convex bearing faces 16. At the upper ends of 95 these bearing faces the abrupt downwardly inclined shoulders 17 are formed. The purpose of this particular construction of the

mandrel will become fully apparent as the description proceeds.

The cutting bits illustrated in detail in Fig. 6 each consists of the bit blade or body 18 which is formed upon one end of a longitudinally extended rectangular shank 19. The outer face of the bit body is slightly inclined outwardly with relation to the longitudinal axis of the shank and is rounded or convex as shown. These bits are provided upon their inner faces and at their lower ends with the gradually widening lapping flanges 18' as clearly illustrated in Fig. 7, wherein the bits are shown in the relative positions they assume when disposed in working position beneath the well casing. It will be observed that the edges of these flanges are slightly spaced from the body walls of the bits so that they constitute in conjunction with each other a continuous cutting or scraping edge across the bottom surface of the bits, and thereby effectually cut or break up hard substances at the bottom of the well. Each of the bits is also provided with a flattened face on opposite sides thereof as shown at 20. The inner opposed faces of the cutting bits are engaged with opposite sides of the depending web plate 14 on the lower end of the mandrel 5, though they exert but little or no frictional pressure thereon in the operation of the device.

At the juncture of the body or cutting blade of the bit with the shank thereof and upon the outer face of the bit, a protuberance or shoulder 21 is formed. The upper edges of the bit body upon opposite sides of the shank are concave as indicated at 22 and adjacent to the shank at the upper ends of said concave faces, the beveled bearing surfaces 23 are provided. These concave and beveled surfaces of the bit body are complementary to the convex surfaces 16 and the inclined shoulders 17 of the mandrel and bear against the same in the operative positions of the cutting bits. The shoulders 17 coacting with the beveled surfaces of the bits prevent outward or lateral movement of the bits in the rotation of the tool while the convex faces 16 of the mandrel reduce wear upon the depending web 14 to a minimum.

By providing the concave surfaces 22 on the cutting bits to seat against the convex surfaces 16 of the mandrel, longitudinal pressure of the cutting bits when in operation tends to force the same outwardly away from the central web 14 and cause the shoulders 23 of the cutting bits to bear against the shoulders 17 on the mandrel, whereby the wear of the parts is greatly minimized and the device as a whole rendered very strong and durable.

Lugs 24 are formed upon the end of the shank 19 of each of the cutting bits and pro-

ject from opposite faces of said shanks. 65 These lugs are provided with rounded peripheral faces 25 and are adapted to rock upon the inner side walls of the grooves 11 in the stock or mandrel. The shank 19 of each cutting bit is also provided upon the 70 faces thereof whereon the lugs 24 are formed with longitudinal ribs 26, said ribs terminating in spaced relation to the lugs 24. In the insertion of these bits into the mandrel, the shanks thereof are disposed approximately at right angles to the longitudinal axis of the mandrel and the lugs 24 passed through the recesses 13 and into the grooves 11. The cutting bits are now moved downwardly and inwardly, and then forced longitudinally so that the lugs 24 thereon are moved into the upper ends of the grooves 11 and the ribs 26 extended into said guide grooves. The lower ends of the channels 8 in the mandrel are widened to permit the 85 ribs 26 of the bit shanks to move through said channels and in line with the grooves 11. It will further be observed from reference to Fig. 3 that the inner faces of the shanks of the cutting bits are beveled or inclined inwardly toward the body of the bit as shown at 27.

In the bore 6 of the mandrel, a longitudinally movable plunger or stem 28 is mounted. A coil spring 29 is mounted upon the 95 upper end of this stem within the enlarged end 7 of the bore and yieldingly holds said stem against movement. The lower end of this spring bears against the internal shoulder 30 while the upper end thereof bears 100 against the head 31 formed upon the upper end of the stem. The lower end of the stem 28 is provided with a rectangular transverse opening 32, and each of the cutting bits is provided in its shank 19 with a similar opening 33 which is adapted to register with the opening in said stem. The flat rectangular key 34 is insertible through the registering openings of the stem and the bit shanks and is provided in one edge and at its center with 110 a notch 35 to receive the stem 28 at the lower end of the opening 32 therein, said notch providing shoulders to prevent longitudinal movement of the key. It often occurs, however, that the coupling pin or key 115 34 is broken in the operation of the device and the bits will fall downwardly in the mandrel and swing outwardly therefrom or become entirely disengaged from the mandrel and lost in the well hole. To obviate 120 this possible loss of the cutting bits, I provide the mandrel with longitudinal slots 36 which open into the longitudinal channel 8 at each side thereof. After the bits have been inserted in the mandrel, the pins 37 125 are passed through the slots 36 and through coinciding openings 38 formed through the ends of the bit shanks. It will thus be ap-

parent that even if the key 34 is broken, the cutting bits when contacting with the side of the well hole will be forced upwardly so that the shoulders of the bit will engage with the 5 shoulders on the lower end of the mandrel as above explained, thus holding said bits against outward swinging movement, and enabling the same to sustain various strains to which they may be subjected, in the continued 10 operation of the reamer.

In the use of my improved underreamer for reaming the walls of wells beneath the casing or well tube, the cutting bits are pulled downwardly against the tension of 15 the spring 29 so that said bits may be moved inwardly toward each other and beneath the web plate 14 on the lower end of the mandrel. This inward movement of the bits is permitted by the provision of the beveled 20 surfaces 27 on the inner faces of the shanks of the cutting bits and by flaring the lower ends of the grooves 11 of the mandrel which admits of the movement in said grooves of the ribs 26 on the bit shanks. For the purpose 25 of pulling the bits beyond the end of the mandrel so that the bits may be inserted in the upper end of the well casing, a pair of tongs are employed, the jaws of which are adapted to be engaged in the sockets or recesses 30 indicated at 39 which are provided in the outer face of each of the cutting bits. After disposing the bits in this manner, they are inserted into the well tube and forced downwardly therein, the upward pull upon 35 said bits exerted by the spring 29 tending to move the bits outwardly into frictional contact with the well casing. After the shoulders 21 of the cutting bits move beneath the lower end of the well tube, the 40 spring 29 immediately acts to force the stem 28 upwardly in the mandrel and throw the body portions of the bits outwardly upon opposite sides of the web plate 14 and into engagement with the walls of the well. 45 When the bits are extended, the key is disposed in the widened lower ends 10 of the slots 9, and in the outward movement of the bits upon opposite sides of the web 14, this key is freely movable in said widened portions 50 of the slots, thus obviating liability of breakage of the key and also facilitating movement of the bits into the lower end of the well tube when the reamer is drawn upwardly. When the reamer is rotated in the ordinary 55 manner, the well will be reamed or cut away beneath the lower end of the casing. As above stated, the lapping flanges 18' serve to break up the material at the bottom of the well hole which may accumulate 60 beneath the cutting bits, and prevent said bits from being clogged so that the reaming operation may be quickly completed.

From the foregoing, it will be readily seen

that I have materially improved the construction of the device disclosed in my prior patent hereinbefore referred to. When the operation is completed, the reamer may be readily withdrawn by simply pulling upwardly upon the same. The shoulders 21 of the cutting bits engaging the lower end of 70 the well tubing holds said bits while the mandrel moves upwardly within the lower end of the tube. When the lower edge of the depending flange or web 14 reaches the 75 point of juncture of the shanks with the body portions of the cutting bits, the beveled or inclined faces 27 of said shanks move inwardly against the opposite sides of said web, thus permitting the cutting bits to be 80 drawn upwardly within the lower end of the well tube.

The device as a whole is comparatively simple in construction and the various parts thereof may be easily and quickly assembled 85 or disassembled when it is necessary to sharpen the cutting bits.

My improved reamer is also extremely durable and efficient in practical use and may be produced at small cost. 90

While I have shown and described the present preferred embodiment of the invention, it will be obvious that the same is susceptible of considerable modification in the form, proportion and arrangement of the 95 several elements without departing from the essential features or sacrificing any of the advantages thereof.

Having thus described the invention, what is claimed is:

1. In an underreamer, a mandrel having a longitudinal bore and channel on opposite sides of said bore, the body of said reamer being further provided with longitudinal slots of less width than the channels 105 and connecting the same with said bore, the lower ends of said slots being of greater width than the upper portions thereof, cutting bits movable in said channels, a removable key connecting said cutting bits and 110 movable into the wider lower ends of said slots when the bits are extended, a spring pressed stem mounted in the bore of the mandrel, said stem being provided with an opening to receive said key, and means on 115 the mandrel to force said cutting bits outwardly in opposite directions when the same are moved in one direction in said channels.

2. In an underreamer, a mandrel having a longitudinal bore and channels on opposite 120 sides of said bore, the body of said reamer being further provided with longitudinal slots connecting said bore with the channels, the lower end portions of said slots gradually increasing in width, cutting bits movable 125 in the channels in said mandrel, a spring pressed stem mounted in the bore of the mandrel, said stem and the cutting bits hav-

ing rectangular openings corresponding in size and adapted to be brought into register-
ing relation, and a removable key to detach-
ably connect the bits to said stem adapted
for insertion through said openings and hav-
ing a relatively narrow portion for engage-
ment in the opening in said stem, said key
being movable in the wider lower ends of

10
said slots when the bits are in their extend-
ed positions.

In testimony whereof I hereunto affix my
signature in the presence of two witnesses.

WARREN WAGNER.
